DISTRIBUTING APPARATUS FOR BITUMINOUS AND LIKE MATERIAL

George M. Etnyre, Oregon, Ill., assignor to E. D. Etnyre & Co., Oregon, Ill., a corporation of Illinois

Original application August 1, 1940, Serial No. 349,218. Divided and this application June 21, 1944, Serial No. 541,418

3 Claims. (Cl. 299—34)

1

The invention relates to apparatus for distributing such bituminous and like materials as asphalt, road-oil, tar and emulsion employed in road construction and maintenance, and more particularly to an improved distributor bar and its associated conduit and control system.

This application is a division of my copending application Serial No. 349,218, filed August 1, 1940, now Patent No. 2,372,065, issued March 20, 1945.

A general object of the invention is to provide a new and improved distributing apparatus for applying material of this nature to road or like surfaces effectively and which embodies novel relationships of elements for adapting the apparatus to meet differing operating as well as idle conditions.

Another object is to provide new and improved means for effectively draining and clearing the distributing system of residual material without waste.

Another object is to provide in apparatus of this character novel means for supporting the distributor or spray bar for movement to various positions from a normal distributing position at adjustable vertical levels including movement to an inverted position for drainage, to a compactly folded relation for traveling and movement to clear an obstruction.

An additional object of this invention is to provide a distributor bar having a plurality of sections in longitudinal alignment during distributing operation and joined together by connector fittings through which material flows to or from the sections and which are disposed above the bar during distribution and rotatably supported for swinging the bar to a position above the connector fittings for draining material therefrom.

In conjunction with the foregoing, it is an object of this invention to provide walls in the sections of the distributor bar which slope downwardly toward the connector fittings when the bar is in an inverted position for draining.

Other objects and advantages will become apparent in the following description and from the accompanying drawings, in which:

Figure 1 is a fragmentary view showing in side elevation distributing apparatus embodying the features of the invention.

Fig. 2 is a fragmentary view looking toward the rear of the apparatus parts thereof being shown in section.

Fig. 3 is a sectional view on an enlarged scale taken as indicated by the line 3—3 of Fig. 2.

2

Fig. 4 is a sectional view transversely through the distributor means in operative position.

Fig. 5 is a view similar to Fig. 4 showing the distributor means in inverted position.

Fig. 6 is a detail sectional view taken substantially along the line 6—6 of Fig. 7.

Fig. 7 is a diagrammatic view looking toward the rear side of the distributor means in the operative position thereof.

10 Fig. 8 is a similar view but showing the distributor means in inverted position.

Fig. 9 is a similar view showing the distributor means in idle traveling position.

Fig. 10 is a diagrammatic plan view of the distributor means illustrating movement of an end section thereof to clear an obstacle.

While the invention is susceptible of various modifications and alternative constructions, I have shown in the drawings and will herein describe in detail, the preferred embodiment, but it is to be understood that I do not thereby intend to limit the invention to the specific form disclosed, but intend to cover all modifications and alternative constructions falling within the spirit and scope of the invention as expressed in the appended claims.

Since systems embodying the present invention may be used without substantial modifications in conjunction with various types of supply tanks, truck chassis, and control apparatus, it has not been deemed necessary herein to illustrate or describe fully such correlated mechanisms.

In the drawings, the numeral 20 designates a supply tank or reservoir which may be of conventional form supported upon a truck chassis or the like. The chassis may include a rearwardly extending frame illustrated fragmentarily at 21 for supporting certain parts of the distributor system. Near its rear end the lower side of the tank has a valve casing 22 rigidly secured thereto and communicating with the interior of the supply tank. A valve, housed within the valve casing and manipulated by the lever 23, controls the flow of material from the tank. On the other side of the valve casing the flow passage therein communicates with the intake side of a suitable force pump (not shown) which preferably is a gear pump housed within a pump casing 24. A conduit 25 communicates with the downwardly opening pressure side of the pump and leads rearwardly therefrom to communicate with a transverse header 26. At the ends of the header are valve casings 27 housing valves (not shown) having operating stems 28 engageable by control shafts 29 shown only in Fig. 1. These valves con-

trol the flow of fluid material from the header 26 to supply conduits 30 and also to a return line 31 which is connected to an upstanding conduit 32 opening into the supply tank.

The present structure embodies two supply conduits 30 and each supply conduit 30 adjacent to the valve casing 27 includes a connection designated 33 serving as a sump toward which material drains by gravity from the valves and conduits on both sides thereof when not forced otherwise by the pump. From this connection the conduit extends outwardly in a direction transverse to the longitudinal line of the assembly (sidewise of the truck) to a rearwardly extending elbow 34 that communicates through a ball and socket joint 35 with a rearwardly extending conduit section 36 which connects through another ball and socket joint 37 with an elbow fitting 38 (Figs. 1 and 3).

The elbow fitting 38 includes one section arranged for connection in the ball and socket joint 37 and an externally screw threaded flange section 39 which, in assembly, faces transversely outwardly of the center line of the truck. Opposite the flange is a boss 40 having one end of a tubular tie rod 41 seated thereon. The tie rod extends between the bosses 40, thus linking the supply conduits together in definitely aligned relation.

As shown in Fig. 3, the outwardly facing flange section 39 is internally flared as at 42 to receive the complementally tapered flow connector or nose portion 43 of a hollow substantially U-shaped distributor bar connector fitting 44; the flow connector or nose portion 43 communicating with one side of the hollow connecting portion of the substantially U-shaped connector fitting and projecting therefrom. The means, by which the elbow section 39 and the connector fitting 44 are secured together, is of a type which permits of relative rotational movement of the connector fitting about the axis of the flared opening 42 and flow connector portion 43, through which rotational movement the distributor bar is swung as a unit from a distributing position to draining or traveling positions, as shown in Figs. 7, 8, and 9. Thus, an outstanding flange 45 on the connector fitting adjacent to the flow connector or nose portion 43 thereof is in assembly disposed in slightly spaced relation to the end face of the flange section 39 for engagement by an annular flange 46 on a nut 47 engaging the external screw threads on the flange section 39. Preferably, a type of split nut having adjusting screws 48 is employed to maintain a relationship between the connected parts that will be fluid-tight yet permit the connector fitting to rotate relative to the flange section 39.

As may be seen in Fig. 7, the means by which the fluid material is distributed uniformly over an underlying road surface is composed of several sections. As shown, the distributor means, or the distributor bar as a whole, comprises two central sections 49 and two end sections 50. Each section has a plurality of spray nozzles 51 extending in aligned longitudinally spaced relation along one side thereof. This side, during operation, is the lower side of the bar sections. Each of the central and end sections 49 and 50 have inclined upper surfaces 50a so that the material in these sections will drain back into the connector fittings 44 when the distributor bar is inverted. One end of each section is closed and the other end has an angularly disposed connector elbow or annular flange 52 extending outwardly from the side thereof opposite to the spray nozzles.

Each substantially U-shaped connector fitting 44 has a pair of axially spaced annular flanges 53 on one side thereof and at the ends of the legs of the U-shape, the legs of the U-shape extending therefrom in parallelism for connection with the elbows or flanges 52 on the distributor bar sections. This connection with the central bar sections 49 is a rigid one and is obtained in any suitable manner as by providing a collar 54 on the end of the flange 52 of the central section 49 through which securing screws 55 extend into engagement with enlarged margins of the flange 53. The central sections extend toward each other from their connections with the connector fittings 44 and are preferably enclosed within a protective shroud 56.

The end sections 50 are secured to the connector fittings 44 for rotational movement about the axes of the flanges 52, 53, which axes are substantially perpendicular to the rotational axes of the connector fittings 44 to the elbow fittings 38. To this end, each end section elbow or flange 52 has a collar 57 secured thereto for abutting engagement with the end face of the connector fitting flange 53 and the collars 57 have an annular rib 58 engageable by a gland nut 59 screw threaded onto the end of the flange 53. To enable the operator to vary the overall length of the distributor bar, each end section may itself be divided into sections and such sections provided with quickly detachable securing means indicated generally at 60 permitting an end of one length to be removed and replaced by another end of different length.

The distributor bar is preferably mounted for adjustment as a unit to different vertical levels as well as transversely in a direction along its longitudinal axis. Although the vertical and transverse adjustment features are somewhat incidental to the invention covered by this application, they are briefly explained to complete the disclosure and particularly to emphasize the flow conduits and their relation to the drainage and cleaning of the system. Thus, as shown in Figs. 1 and 2, the distributor bar and the supply conduits leading thereto from the ball and socket joints 35 are supported by swinging frames generally designated 61 having substantially universal movement. Depending from each side of the frame 61 is a bracket 62 supporting a transversely extending rod 63. Pivotally mounted on each end of the rod is a link 64 which extends outwardly and downwardly and carries an outwardly extending stud 65. The stud pivotally supports a frame section 65a having vertically spaced bearings 66 thereon. Straddling the bearings 66 and pivotally supported thereby are spaced ears 67 on an end of the swinging frame 61. The axes of these pivotal connections are located substantially on the transverse plane that includes the center of movement of the ball and socket joint 35. The frame extends rearwardly from these pivotal connections and at its other end has spaced ears 68 which pivotally support between them by a stud 71 a block 69 having arms 70 (Figs. 2 and 3) extending inwardly from the elbow fitting 38.

The means by which the swinging frame 61 is shifted transversely is not herein shown. Vertical movement of the distributor bar to various levels may be manually effected through a rock shaft 73 mounted on the bracket 62 and movable manually by an operator's handle 74. A lever arm 75 on the rock shaft is connected by linkage 76, 77 with the frame section 65a, the arrange-

ment being such that movement of the rock shaft in one direction or the other will shift the swinging frame 61 about the pivots 63, 65 to raise or lower the distributor bar.

As shown clearly in Figs. 1 and 2, the supply conduits 30 and the distributor bar, including the sections 36 and the various connections, are upwardly inclined from the sumps or connections 33 to produce drainage of residual material toward those connections or sumps. Means is provided for insuring that this upwardly inclined relationship will be present in any vertical position of adjustment of the distributor bar. In the present instance, this means is in the form of a quadrant 78 associated with the operator's handle 74 and so arranged with respect thereto that one end of the quadrant, designated 79, forms a stop for limiting the downward swinging movement of the frame. In the present instance, the lowermost position is substantially limited to one in which the line between the centers of the ball and socket joints 35 and 37 falls along the line designated 80 (Fig. 1). The highest maximum movement of the frame is designated by the line 81.

During the distributing operation, the distributor bar as a whole extends downwardly from the elbow fittings 38, movement to this position being permitted by rotation of the connector fittings 44 relative to the fitting 38 to a position in which the distributor bar is below the connector fittings and the nozzles face downwardly. This position of the distributor bar is shown in Figs. 4 and 7. To drain the distributor bar, it is swung upwardly about the axis of the flow connectors or nose portions 43 of the connector fittings 44, which axis is substantially parallel to the distributor bar, to an inverted position in which, as shown in Fig. 5, the distributor bar is above its axis of rotation and the connector fittings. This swinging movement may be effected in any suitable manner as by an operating link 82 (Figs. 1 and 4) pivotally connected to an ear 83 on one of the central bar sections and an operating lever 84.

Such means as a chain 85, connected to the lever 84 and arranged for engagement along its length by a hook or the like (not shown), may be employed to maintain the distributor bar in any position above the distributing position shown in Fig. 4. If desired, a stop lug 86 may be secured to the link 82 for engagement with one of the elbow connectors 38. The lug is arranged to prevent the link 82 from swinging into engagement with the connector elbow when the distributor is released to swing downwardly, which engagement, unless prevented, might bend the link. The engagement of the lug 86 with the connector elbow acts in conjunction with the link 82 to restrain the distributor bar against incidental swinging movement.

In its inverted position, all of the residual material in the distributor and in the supply conduits leading thereto is above the points of connection of the supply conduit 30 with the connections 33 which serve as sumps and the material will, therefore, drain toward these points by gravity. Preferably, means is provided for withdrawing material from the sumps provided by the low points of the connections 33 and discharging it into the tank. Thus, the valve casing 22 is provided with a filling conduit 87 through which, by a proper arrangement of the valves in the valve casings 22 and 27, material from an outside source may be drawn through the filling conduit 87 and pumped into the supply tank 20 through

conduit 25, header 26, return line 31 and conduit 32. The filling conduit 87 when not in use is arranged to be closed by a suitable cap (not shown). A valve casing 88 communicates with the filling conduit 87 and a valve in the casing (not shown), having an operating stem 89, is arranged to establish communication between the filling conduit and a pair of pipe lines 90. Each of these lines leads to one of the sumps or connections 33 and opens near the bottom thereof. When the system is set as above described to fill the supply tank, but with the filling conduit 87 capped and the valve in the valve case set to connect the lines 90 with the filling conduit, the pump will draw all of the residual material out of the distributor bar and the supply conduits leading thereto and return such material to the supply tank. Thus, the operator, by merely inverting the distributor bar, can effectively clean the system without wasting the material.

As has been mentioned, the end sections 50 of the distributor bar are rotatable with respect to the connector fitting 44. When the distributor bar is in its depending operative position, as shown in Fig. 10, the axes on which the end sections are mounted are vertical. This arrangement permits either end section to swing rearwardly to clear any obstacle 91 that it may encounter during movement of the apparatus along the road. Swinging movement in a return direction may be effected in any suitable manner as by elevating the distributor bar slightly so that an unaligned end section will swing back by gravity or by spring means (not shown). The return movement is limited by such means as stop fingers 92 carried by the end sections for engagement with a part of the adjacent central section.

Another important feature resulting from the relationship of the axes of the distributor bar and the end sections is that it permits the distributor bar to be quickly placed in condition for traveling to and from a point of distribution. With reference to Fig. 9, the distributor bar may be arranged for traveling by merely swinging the bar about its transverse axis to a position in which the spray nozzles face rearwardly and have a slight upward inclination so that the connector fittings slope downwardly from the distributor bar to flow passages. The end sections may then be swung upwardly about their then horizontal axes to slightly inwardly inclined positions as determined by such means as stop lugs 93 on the frame 21. For added security, means may be provided for more firmly connecting the end sections to the frame. In this position the end and intermediate sections tend to drain any residual material through the connector fittings to the pump.

I claim as my invention:

1. In distributing apparatus of the character described, the combination of distributing means including a plurality of elongated substantially longitudinally aligned sections, means for supplying material to be distributed to each of said sections, means for supporting each of the end sections of said distributor means for swinging movement on a vertical axis during a distributing operation, and means for swinging said distributor means as a whole to a position in which
2. said vertical axis approaches a horizontal position so that an end section that has swung about its axis will by gravity return to its normal aligned position, said means for swinging said distributor being operable to return said distributor as a whole to a position in which the axes about

which said end sections swing are in a substantially vertical position.

2. In distributing apparatus of the character described, the combination of a distributor bar including longitudinally aligned intermediate and projecting end sections, means including a supply tank, a pump and conduits for supplying material for distribution through each of said sections, said projecting end sections each being connected at one end to an end of the intermediate section through the legs of a substantially U-shaped connector fitting, the substantially U-shaped fittings each including connector means providing a flow passage communicating with the connecting portion thereof intermediate the legs and angularly disposed with respect to the legs, said distributor bar being normally below said fittings during the distribution of material, means supporting said bar and fittings for swinging movements as a unit about a horizontal axis extending through said connector means to an inverted position in which said fittings are below the bar, said conduits being connected to said connector means and sloping downwardly therefrom to a sump, the sections of said distributor bar including walls sloping downwardly toward said fittings when the bar is in said inverted position, whereby in said inverted position of the bar the sections thereof drain by gravity through said fittings to said sump, and means including 30 said pump for pumping the material from the sump to the supply tank.

3. In apparatus of the character described, the combination of a distributor bar having a row of spaced nozzles on one side thereof and con- 35

nector elbows at the ends extending from the bar in a direction away from the nozzles, connector fittings having flow passages adjoining and connected to said elbows and having angularly extending portions substantially parallel to the distributor bar, said angularly extending portions having a common axis, means supporting said angularly extending portion for rotary movement about said axis to swing the distributor bar between positions in which the nozzles face downwardly and upwardly, and partitioning means in said distributor bar dividing the bar into sections and providing walls in said sections sloping downwardly toward said elbows from adjacent ends of the sections when the distributor bar is in a position such that the nozzles face upwardly, whereby said sections drain by gravity through said elbows and fittings.

GEORGE M. ETNYRE.
